JOSEPH H. DICKINSON, OF CRANFORD, NEW JERSEY, ASSIGNOR TO THE AEOLIAN COMPANY, OF NEW YORK, N. Y., A CORPORATION OF CONNECTICUT.

VOLUME-CONTROLLING MEANS FOR MECHANICAL MUSICAL INSTRUMENTS.

No. 926,171

Specification of Letters Patent.

Patented June 29, 1909.

Application filed December 16, 1905. Serial No. 291,974

To all whom it may concern:

Be it known that I, JOSEPH H. DICKINSON, a citizen of the United States, and a resident of Cranford, in the county of Union and State of New Jersey, have invented certain new and useful Improvements in Volume-Controlling Means for Mechanical Musical Instruments, of which the following is a specification.

10 My invention relates to pneumatically operated musical instruments, and particularly to means for controlling the volume of sound produced by modifying the force supplied to various note-sounding devices, or to groups of such devices.

It has for its object to so control the note-sounding devices either by the hand of the operator or automatically by means of perforations in the music sheet.

20 It consists of means to these ends, including means by which the operator of the manual controlling device throws the sheet actuated controlling device out of operation, and of novel valves and combinations of parts hereinafter described.

In illustrating and describing the preferred mode of constructing and operating my invention I will refer to a pneumatic musical instrument player, which may be 30 incorporated with, or wholly or partially separated from a piano, organ or other instrument. As such players in many forms are well known in the art, I have shown in the drawings only so much of the device as 35 is necessary to explain my invention.

Figure 1 is a partial front view of a player, the casing being removed. Fig. 2 is an enlarged partial view of the tracker and of a perforated music sheet. Fig. 3 40 is a front elevation, partially in section, of a valve casing, valve and actuating mechanism therefor. Fig. 4 is a view, partially diagrammatic and partially in section through the line 4-4, Fig. 1. Fig. 5 is a 45 horizontal section through the line 5-5, Fig. 1. Fig. 6 is a vertical section through the plane 6-6, Fig. 5. Fig. 7 is a partial front elevation of parts shown in Fig. 5. Fig. 8 is a plan view of the valve and valve seat 50 shown in Fig. 7. Fig. 9 is an elevation of a manually operated valve detached from the device. Fig. 10 is a vertical section of details on the plane 10-10, Fig. 9. Figs. 55 11 and 12 are plan views showing different positions of the valve shown in Figs. 9 and

10. Fig. 13 is a side elevation of the valve shown at the left of Fig. 2. Fig. 14 is a vertical section of a portion of the pneumatic action of the player showing its connection with a valve chamber for modifying the sound produced.

1 Fig. 1 designates a valve casing, leading from which is a series of tubes or connections 11, each of which leads to a valve chamber connected with one of the note-sounding or striking pneumatics of the instrument, as hereinafter described. Within the bore of the casing 1 slides a valve 12 having a tubular stem 13 and a lateral port 14. As shown, the port 14 is adapted to communicate in turn with each of the ports which terminate the tubes 11. Connected to the ends of the casing 1 are tubes or pipes 16, 17, leading to a chamber 2, while the free end of the tubular stem 13 is also connected by a flexible tube 18 to the chamber 2, which is in turn connected by a tube 20 to a source of pneumatic force, in this case a suction wind chest 32. This wind chest 32 and the normal or low tension wind chest 33 are indicated in Fig. 1 of the drawings. The tubular stem 13 is connected by a link 19 to a hand lever 15, by means of which the valve 12 may be moved to connect the port 14 with any of the tubes 11, as desired. It is evident that by a slight change of size or arrangement the valve 12 may be made to communicate simultaneously with a small group of the tubes 11, instead of communicating with a single tube, as shown. Also connected to the lever 15 by a series of links and a lever is a pointer 15* adapted to move transversely over the music sheet, as shown in Fig. 1. As this pointer and its connections form no part of the present invention they need not be numbered or further described. In the chamber 2 are two valves 21, 22, adapted to connect the respective ends of the valve casing 1 through the tubes 16 and 17, either with atmosphere or with the suction chamber 2. The diaphragm pneumatics by which the valves 21, 22 are moved are connected respectively by tubes 23, 24 to ports 40, 41 in a valve seat 4, and in addition by tubes 50, 51 to ports 52, 53 in a second valve seat 5.

On the valve seat 4, shown in Figs. 1, 4, 7 and 8 of the drawings, rests a valve 42 shown as a flat bar having sliding contact with the face of the seat 4. The valve 42 is moved to cover and uncover the ports 40 and 41.

41 by means of four bellows pneumatics 61, 62, 63 and 64, shown in Figs. 1, 3, 4, 5 and 7 of the drawings. As shown, the valve 42 is pivoted at its middle point to a spring lever 43 which is pivoted on a post 44 on the valve seat 4. As shown in Fig. 7, the lever 43 serves as a spring to hold the valve 42 to its seat as well as to move the valve in a manner to be hereafter described.

- 10 As shown in Figs. 4 and 7, the effect of collapsing the bellows 61 will be to press in the left end of the valve bar 42 so as to uncover the port 40. The bellows 62 acts to force the bar 42 directly back against the pin 45 on the seat 4 so as to uncover both ports 40, 41. The collapsing of the bellows 63 acts to force back the right end of the valve 42 so as to uncover the port 41. Finally, the collapsing of the bellows 64 acts 20 through the lever 43 to force the valve bar 42 to its forward position shown in Fig. 8, in which both ports 40, 41 are covered.

The bellows 61, 62, 63 and 64 are connected by means of passages 65 to a valve chamber 7, in which are four diaphragm valves 71, 72, 73, 74 (see Figs. 4 and 6). These valves are moved to alternately admit air or suction to the bellows 61, 62, 63 and 64 respectively by diaphragm pneumatics in 30 the usual manner, as shown in Fig. 6. Air is admitted to raise these diaphragms through tubes 75, 76, 77, 78 leading to ducts 75^x, 76^x, 77^x and 78^x respectively in a tracker 70. In addition to the valves 71, 72, 73, 74, 35 the valve chamber 7 contains a valve 79, the diaphragm of which is normally raised by air admitted through a passage 710 controlled by the valve 74. A second passage 711 leads from the compartment 712 in the 40 chamber 7 in which the valves 74 and 79 are placed to the compartment 713, in which are the valves 71, 72, 73.

The valve seat 5 with which the valves 21, 22 of the chamber 2 are also connected is provided in addition to the ports 52, 53, already described, with a third port 54, from which a tube 55 extends to the chamber 8 of a manual relief valve to be hereafter described. On the valve seat 5 rests a valve 56, shown as 50 a flat bar similar to the valve 42. It is moved to uncover these ports 52 or 53 alternately or all the ports 52, 53, 54 at the same time by a manual device (see Figs. 1, 9 and 10) comprising four levers 57, 58, 59, 510 55 provided at their upper ends with push buttons 57^x, 58^x, 59^x, 510^x, which as shown, project through a stationary part of the instrument itself adjacent to and below the tracker 70.

60 As will be seen in Figs. 9 and 10, the levers 57 and 58 act to force back an end of the valve 56 so as to uncover the ports 52 and 53 respectively, together with the central port 54 in either case, as shown in dotted 65 lines, Fig. 12. The lever 59 moves the valve

56 integrally to uncover all the ports 52, 53, 54 (see full lines, Fig. 12) while the lever 510 replaces the valve 56 to close all the ports, as shown in Fig. 11. It will be seen that the lower member of the bent lever 510 acts as a spring to hold the valve 56 to its seat 5. Both the valve seats 4 and 5 are provided with stop pins, as shown in Figs. 8, 11 and 12, to limit the movement of the valves 42 and 56 respectively.

I have described a tube 78 as leading to a duct 78^x in the tracker 70. In the present form of the invention, however, the tube, while it leads to the duct 78^x, does so indirectly through a valve chamber 8, shown in Figs. 1, 2 and 13 of the drawings, from which a tube 781 passes directly to the duct. As already described, this valve chamber 8 is also connected by a tube 55 with the port 54 in the valve seat 5. The chamber 8 may be opened to atmosphere by the lifting of a valve 81, which is effected by means of a cam 82 on the shaft 83, the bent end 84 of which forms a handle convenient to the operator and adjacent the side of the music sheet 9.

In Fig. 14 I have shown a portion of the action casing of the player to illustrate a mode of increasing the pneumatic force supplied to the striking pneumatics. One of the tubes 11 is shown as leading to a diaphragm chamber 91 in the casing 92. This casing is provided with longitudinal suction chambers 93 and 94 connected respectively to sources of "high" and "low" wind, *i.e.*, air under relatively high and low tensions. A valve 95 is carried by the diaphragm 96 which closes 100 100 105 110 115 120 125 130 135 140 145 150 155 160 165 170 175 180 185 190 195 200 205 210 215 220 225 230 235 240 245 250 255 260 265 270 either side of the valve 12 in whatever position this may be at any given time. In the present instance, the ends of the casing 1 are respectively connected to the suction chamber 2 by means of the tubes 16, 17. When it is desired to admit air to the right end of the chamber 1 through the tube 17, the operator presses the button 57^x, shown in Figs. 1 and 9 of the drawings, whereby the left end of the bar 56 is pressed forward, as shown in dotted lines, Fig. 12. This uncovers the ports 52 and 54 in the valve 5. Air then passes through the port 52 and tube 50 and acts on the diaphragm pneumatic shown at the right of chamber 2, Fig. 3, to raise the valve 22. The upper portion of this valve admits atmospheric air to the tube 17, while the lower portion of the valve cuts off connection between the tube 17 and the suction chamber. In the same way the pressure of the operator's fingers on the button 58^x will open the port 53 to permit the passage of air through the tube 51, which acts in a similar manner to raise the valve 21 in the chamber 2 and permit the passage of air through the tube 16 to the left end of the valve casing 1. When the operator presses on the button 59^x the valve 56 will be moved integrally forward, as shown in full lines, Fig. 12, to admit air to both ports 52 and 53, as well as to the port 54. In this case both the valves 21 and 22 will be raised and air will be admitted to both ends of the valve casing 1 through the tubes 16 and 17. In like manner, by pressing the button 510^x, the operator is enabled to return the bar 56 to the position shown in Fig. 11 of the drawings, in which air is cut off from all the ports 52, 53, 54, when the valves 21, 22 will return to the position shown in Fig. 3 of the drawings, and both tubes 16, 17, and the respective ends of the valve casing 1 with which they are connected, will be connected to the suction chamber 2. I have thus far omitted to describe the effect caused by the entrance of air to the port 54, as it is preferable first to describe the operation of the automatic features of the device.

I have shown the chambers beneath the pneumatic diaphragms which act to raise the valves 21, 22 as connected by tubes 23, 24 to ports 40, 41 respectively in a valve seat 4. These ports are opened and closed by a valve bar 42, shown in Figs. 1, 4, 7 and 8 of the drawings. The movement of the valve 42 on its seat 4 is similar to that of the valve 56 on its seat 5, already described. The left end of the bar 42 is pressed backward to uncover the tube 40 when desired by means of a finger 61^x attached to the front or movable board of a pneumatic bellows 61. In the same way the right end of the valve 42 is pressed backward to uncover the port 41 by the collapsing of the bellows 63. It is obvious that the collapsing of the bellows 61,

whereby air is admitted to the port 40, will by reason of the passage of air through the tube 23 raise the valve 21 and connect the tube 16 and the left end of the casing 1 with atmosphere, and that a similar movement of the bellows 63 will connect the right end of the casing 1 through the tube 17 with atmosphere by reason of the lifting of the valve 22 in the chamber 2. It will be seen that the finger 62^x on the intermediate bellows 62 is of sufficient width to press backward the entire valve 42 integrally, while the collapsing of the bellows 64, shown at the right of Fig. 7, acts through the lever 43 to return the valve to its normal position shown in Fig. 8 of the drawings, in which both ports 40 and 41 are covered, and in which case, of course, both ends of the valve casing 1 are connected to the suction chamber 2.

The method of collapsing the bellows 61, 62, 63 and 64 as desired will now be explained.

Immediately adjacent the bellows 61, 62, 63 and 64 is a board 7 in which are two valve chambers 712, 713. In the valve chamber 713 are three diaphragm valves 71, 72, 73. In the valve chamber 712 is a diaphragm valve 74 and an additional valve diaphragm 79. It is understood that the chambers 712 and 713 are both connected by any convenient means, not shown, to a source of wind tension, preferably the wind chest 32. The diaphragm pneumatics below the valves 71, 72, 73, are connected respectively by flexible tubes 75, 76, 77 to ducts 75^x, 76^x, 77^x respectively in the tracker 70 of the instrument. The diaphragm pneumatic below the valve 74 is connected by the tube 78 to the valve chamber 8, as shown in Fig. 2, and this valve chamber is connected by a tube 781 to a duct 78^x in the tracker. The music sheet 9 shown in Figs. 1 and 2 of the drawings is provided in addition to the usual note-actuating perforations 91 with four rows or series of perforations 95, 96, 97, 98, adapted, as the sheet passes over the tracker, to register respectively with the ducts 75^x, 76^x, 77^x, and 78^x. When a perforation 95 passes over the duct 75^x air will pass through the tube 75 and act through the diaphragm pneumatic to raise the valve 71, thus cutting off the passage of air through the tube 65 to the bellows 61 and connecting the bellows 61 with the suction chamber 713. The consequent collapsing of the bellows 61 will act to move the left end of the valve bar 42 to uncover the port 40, by which, as already explained, the valve 21 in the chamber 2 is raised and air admitted to the left end of the valve casing 1, and hence to such of the tubes 11 as happen at the time to be at the left of the valve 12. In the same way the passage of a perforation 97 over the duct 77^x will act through the movement of the 130

valve 73 to collapse the bellows 63 to raise the valve 22 and admit air through the tube 17 to the right end of the valve casing 1. In like manner the perforations 96 of the 5 music sheet 9 act to collapse the bellows 62 which moves the bar 42 inwardly to uncover both the ports 40 and 41, and thus to admit air to both ends of the valve casing 1 and to all the tubes 11 connected therewith, except the tube or tubes covered by the valve 12. Similarly, a perforation 98 in the sheet 9 passing over the duct 78^x in the tracker 70 passes air through the tube 781, valve 10 chamber 8 and tube 78 to lift the valve 74 in the casing 7. This acts in the manner already described to move the valve bar 42 to its forward position shown in Fig. 8 of the drawings, thereby closing both the ports 40 and 41, whereby both the valves 21 and 20 22 are lowered to the position shown in Fig. 3 of the drawings, and both ends of the valve casing 1 are connected through the tubes 16 and 17 to the suction chamber 2. The valve 74 has the additional function of opening 25 the passage 710 in the block 7 to the suction chamber 712, as shown in Fig. 6. This acts to depress the valve 79, thereby opening it to atmosphere. The air then passes through the passage 711 to the chamber 713 in the 30 block 7, thereby depressing the diaphragm pneumatics connected to the valves 71, 72, 73, and opening these to air by which the bellows 61, 62, 63, if any of them happen to be collapsed at the time, are promptly expanded. In this way they offer no opposition 35 to the collapsing of the bellows 64, by which the bar 42 is moved.

It will be seen that two independent means are provided for the admission of air to the 40 respective ends of the valve casing 1. One of these is manual so that the player or operator may determine the force to be given the striking pneumatics of the instrument as he wills. The other is automatic, *i. e.*, it 45 is controlled by the additional perforations in the music sheet. To render these two methods alternative, that is, to prevent any action of the perforations 95, 96, 97 and 98 in the music sheet when the player desires 50 to use his own taste and skill in determining the force of the striking pneumatics, is the object of the valve chamber 8. As already explained, the movement of the valve 56 to uncover either of the ports 52 or 53, or both 55 of them, also uncovers the middle port 54. This admits air through the tube 55 to the valve chamber 8 and thence through the tube 78 to raise the valve 74. By the consequent collapse of the bellows 64 the valve 60 42 is moved to its forward position (see Fig. 8) to cover both the ports 40 and 41. In this case, the movement of the valves 21 and 22 is caused to depend solely on the air admitted through the tubes 50 and 51, which are connected to the manual device. Or the

player may at any time by means of the lever 84 raise the valve 81 (see Figs. 2 and 13) and thus admit air to the chamber 8, whence it passes through the tube 78 to raise the valve 74 with the result just described. It will be seen, therefore, that the music sheet may be unprovided with the additional perforations for registering with the ducts 75^x to 78^x inclusive in the tracker, or if the player desires to disregard these 75 perforations, he may by raising the valve 81 effectively cut out the operation of these 76 perforations and use the buttons 57^x, 58^x, 59^x and 510^x to open and close the ends of the 77 valve casing 1 to atmosphere at will. 80

It will be understood that in whichever way one of the valves 21, 22 is raised the effect will be to admit air to those tubes 11 which are at the time on the left or the right side, according to which of these valves is 85 raised, of the valve 12. Air so passing through a tube 11 acts in the present instance to raise the diaphragm 96 (see Fig. 14) and thus to cut off the connection between the "low wind" chamber 94 and the 90 chamber 97 and to connect the latter with the "high wind" chamber 93. If then a 95 perforation in the music sheet admits air through the corresponding tube 98 to raise the valve 99, the corresponding striking 100 pneumatic 100 will be operated with an increased force varying with the difference 105 between the degrees of suction in the chambers 93, 94. It is of course obvious that the admission of air to the groups of connections 100 11 at each side of the valve 12 in the valve casing 1 is entirely independent of the movement of the valve in that casing, such valve movement forming the subject of previous 105 patents, as already set forth. It will also be understood that it is optional in constructing the apparatus, whether the increase of 110 pressure in the connections 11 shall cause the increase or the decrease of the tone volume or accent, it being, in my opinion, 115 preferable to have it cause a decrease of the tone volume so as to have the note-sounding devices that are under the immediate control of the port 14 of the valve 12 sound their notes louder rather than softer than the 115 notes above and below and thus facilitate the accenting of a theme or single part of a musical composition. It is also obvious that though I have described the device as acting 120 under suction and as admitting air to the groups of connections 11 at the ends of the valve casing 1, it may by slight changes within the mechanical skill of any one familiar with the art be arranged to work with air pressure instead of suction and to admit to the valve casing 1 and to the connections 11 pressure either greater or less than that of atmosphere. It is also clear that many 125 considerable mechanical changes may be made in the device without departing from the 130

spirit of the invention, and that a part or parts of the device may be used independently of the others.

It will be understood that my present invention provides in addition to the known means for accenting a solo note or small group of notes and for shifting the point of such accentuation, means both tracker controlled and manually controlled for accenting the notes at either side of a dividing means, which dividing means may be movable. In addition, it provides for alternative operation of said last-named accenting means either through the tracker or manually, as required, and means for preventing the interference of the tracker controlled means with the manual means when these latter are being employed.

What I claim is:—

1. In musical apparatus, a series of pneumatic connections for the notes to be sounded, means for varying the pneumatic force supplied to groups of said connections, a tracker having apertures in addition to those connected with the ordinary note-sounding pneumatics, a valve controlling a plurality of passages leading to said force varying means, and means controlled by a perforated music sheet passing over said tracker and coöperating with said additional apertures for moving said valve to alternatively open either of said passages and also to open and close all of said passages.

2. In musical apparatus, a series of pneumatic connections for the notes to be sounded, a tracker, means for supplying pneumatic force, means for dividing said connections into groups, and means controlled by a perforated music sheet passing over said tracker and including a unitary valve and means including a plurality of pneumatics for moving said valve for directing such pneumatic force to a group of said connections on either side of said dividing means, or simultaneously to both such groups.

3. In musical apparatus, a series of pneumatic connections for the notes to be sounded, a tracker, means for supplying pneumatic force, moving means for dividing said connections into groups, and means controlled by a perforated music sheet passing over said tracker and including a unitary valve and means including a plurality of pneumatics for moving said valve for directing such pneumatic force to a group of connections on either side of said dividing means, or simultaneously to both such groups.

4. In musical apparatus, a series of pneumatic connections for the notes to be sounded, a tracker, means for supplying pneumatic force, means for conducting such pneumatic force to a relatively small group of said connections, and means controlled

by a perforated music sheet passing over said tracker and including a unitary valve and means including a plurality of pneumatics for moving said valve for directing such force to a group of said connections on either side of said conducting means, or simultaneously to both such groups.

5. In musical apparatus, a series of pneumatic connections for the notes to be sounded, means for varying the pneumatic force supplied to groups of said connections, a tracker, a valve controlling a plurality of passages leading to said force varying means, and means controlled by a perforated music sheet passing over said tracker and including a unitary valve and means including a plurality of pneumatics for moving said valve to alternatively open either of said passages and also to open and close all of said passages.

6. In mechanical musical apparatus, an accenting device, pneumatic passages leading to said device, a valve controlling a plurality of said passages, and pneumatically operated means for alternatively opening either of said passages and also for simultaneously opening and closing all of said passages.

7. In mechanical musical apparatus, an accenting device, pneumatic passages leading to said accenting device, a valve controlling a plurality of said passages, and manually operated means for alternatively opening either of said passages and also for simultaneously opening and closing all of said passages.

8. In musical apparatus, the combination with note playing mechanisms, tracker-controlled means for actuating the respective note playing mechanisms, and means for accenting some of the notes differently from others, of a tracker-duct and means controlled thereby for varying the volume of sound of a given group of notes relatively to another group, and a separate duct and means controlled thereby for restoring the volume-controlling means to their initial condition.

9. In musical apparatus, the combination with note playing mechanisms, tracker-controlled means for actuating the respective note playing mechanisms, and means for accenting some of the notes differently from others, of a tracker-duct and means controlled thereby for varying the volume of sound of a given group of notes relatively to another group, a separate duct and means controlled thereby for restoring the volume-controlling means to their initial condition, and manually controlled means for controlling such volume independently at will.

10. In combination with note sounding devices, means for accenting or differently sounding two or more groups of the devices, including a tracker, ducts additional to the

- individual note ducts, means controlled by the said additional ducts for automatically accenting notes of either group differently from the other group, or alike and manual 5 means for independently controlling the sounding of the groups differently or alike at will and simultaneously rendering inoperative all the said automatic tracker controlled means.
- 10 11. In combination with note sounding devices, automatic tracker controlled means for varying the volume or intensity of the sound of different groups of note sounding devices, and manually controlled means for 15 doing the same and simultaneously rendering the automatic means inoperative in respect to all the said groups.
12. In combination in mechanical musical 20 apparatus with means for accenting some notes above others simultaneously sounding, means for shifting the point or points of accentuation in the musical scale, tracker controlled automatic means for controlling the said accenting, and manually controlled 25 means for also controlling the said accenting and simultaneous rendering inoperative the automatic means.
13. In combination with mechanical note 30 sounding devices, means for accenting one or more notes separately from those musically above and below it, a tracker board and ducts and means controlled thereby for automatically varying the sounding of a range of notes adjacent musically to the said 35 one or more notes, and manual means for doing the same and rendering inoperative the last said automatic control.
14. Volume controlling means for mechanical 40 musical instruments, having note sounding devices, shiftable means for dividing the note sounding devices into variable groups or ranges, a tracker duct and means con- 45 trolled thereby for automatically varying the sounding of one of the said ranges of notes, another tracker duct and means controlled thereby for automatically varying the sounding of another of the said ranges of notes separately therefrom, and a tracker duct and means controlled thereby for simultaneously and similarly varying both the 50 last said ranges of notes.
15. Volume controlling means for mechanical 55 musical instruments, having means for sounding the respective notes and means for accenting some of the notes above the others, comprising means for shifting the point or points of accentuation in the musical scale, a tracker duct and connections for simultaneously controlling the accenting of two of the ranges of notes, and separate tracker 60 ducts and connections for controlling the accenting of the said two ranges respectively and separately.
16. Volume controlling means for mechanical 65 musical instruments, comprising means for sounding the respective notes, adjustable means for separately accenting a variable range of one or more notes and tracker controlled means for controlling the accenting of one or more other ranges of the notes 70 so as to sound equally with or differently from the first said range, the last said means comprising one or more tracker ducts for increasing the sound or accentuation and one or more separate tracker ducts for decreasing the accentuation.
- In testimony whereof I have signed this specification in the presence of two subscribing witnesses.
